DUAL-CYLINDER VEHICLE LIFT

It is the most important object of this invention to provide a heavy-duty vehicle lift which is portable but yet which may be utilized to lift loaded trucks, trailers and the like at the axle, the lift having a base and a pair of shiftable cylinders on the base, the cylinders being interconnected by a pair of spaced, vertical plates which cooperate with the cylinders to define a well, there being a lift post received within the well and selectively vertically adjustable therein whereby the overall height of the lift may be determined, depending upon the particular use to which it is to be put.

It is yet another object of this invention to provide a common top for the pair of cylinders, the top having a handle pivotally connected thereto, the handle being L-shaped and presenting a minor leg and a major, longer leg, the handle being swingable with respect to the top whereby the major leg may be positioned in overlying relationship to the top for purposes of storage.

Yet another aim of this invention is to provide, in a vehicle lift, a plumbing system for delivering compressed air from an outside source to the cylinders of the lift, the plumbing system being integrated into the lift in such a way that no unsightly pipes, hose or the like are exposed, the plumbing system including a tubular handle to which air is delivered through a valve from an outside source, a pivotal connection between the handle and the top of the lift, said pivotal connection being suitably provided with passageways whereby air may move therethrough and along beneath the top of the lift and into each of the cylinders whereby to enter a space defined between the lower surface of the top and a piston and packing seal which are fixedly held with respect to the base, all to the end that the cylinders may be simultaneously shifted from a lowered position to raised positions as determined by the operator of the lift.

Other objects of this invention include details of construction; the manner in which the components of the lift are assembled relative to one another, whereby metal-to-metal contact between such components is avoided; and the assembly of the lift in such a manner that it may tolerate a considerable amount of angular misalignment, all of which will become apparent from the following specification.

In the drawing:

FIG. 1 is a top plan view of a vehicle lift, portions being fragmentarily illustrated and shown in cross section for clarity of disclosure;

FIG. 2 is a sectional view taken along line 2—2 of FIG. 1;

FIG. 3 is a sectional view taken along line 3—3 of FIG. 2;

FIG. 4 is a fragmentary, elevational view of the connection between the handle and the lift; and

FIG. 5 is a sectional view taken along line 5—5 of FIG. 4.

The vehicle lift, broadly designated by the numeral 10, includes as its primary components, a base 12 which is in the nature of a flat plate, the base having a pair of cylinders 14 and 16 disposed thereon in longitudinally aligned relationship, the cylinders 14 and 16 being shiftable with respect to the base 12 and primarily defining the shiftable portion of lift 10. Cylinder 14 carries a normally forwardly extending bracket 18 which receives axle 20 whereby to mount a pair of metal wheels 22 on said cylinder 14, said front wheels being utilized primarily in positioning the lift 10 with respect to the load to be lifted.

Cylinder 16 carries a pair of spaced, normally rearwardly projecting extensions 24 which receive in transverse relationship thereto an axle 26 whereby to rotatably carry spaced, semipneumatic wheels 28, which wheels are of larger diameter than wheels 22 and are primarily utilized in moving the lift 10 from one position to another. Wheels 28 also cooperate with wheels 22 as an aid in positioning the lift 10 with respect to the particular load to be lifted.

The bracket 18 is secured to the outer surface 30 of the cylinder 14, and the extensions 24 are secured to the outer surface 32 of the cylinder 16. Each of the cylinders is annular in configuration and is independently encased by its circumscribing wall, the wall 34 of cylinder 14 having outer surface 30 and an inner surface 36, and the wall 38 of cylinder 16 having outer surface 32 and an inner surface 40.

The adjacent outer surfaces 30 and 32 of the cylinders 14 and 16 are joined by a pair of spaced-apart, vertically disposed plates 42 at a position centrally of the base 12, the plates 42 cooperating with the outer surfaces 30 and 32 of the cylinders 14 and 16 to define a centrally positioned well 44. The well 44 receives a lift post 46 therewithin in a manner clearly shown in FIGS. 2 and 3 of the drawing, the lift post extending through the top 48 of the lift, which top 48 is common to both cylinders and has an opening 50 formed therein in a central position whereby to permit the lift post 46 to be positioned within the well 44.

The lift post 46 is provided at its upper end with a lift pad 52 and the walls of the lift post which are next adjacent the vertical plates 42 are provided with a series of apertures 54 which are selectively alignable with opposed, aligned holes 56 which are formed in the vertical plates 42. As is evident, the foregoing construction permits the lift post 46 to be selectively and vertically adjusted within the well 44 therefor, permitting the desired positioning of lift pad 52 with respect to the top 48 of the lift 10, all to the end that several different overall heights of the lift may be provided, depending upon the load to be lifted and the position thereof. Thus, the lift post 46 might be adjusted to its lower position if the lift were to be used for raising a truck tractor by the front axle thereof, but yet might be moved to one of its raised positions if the lift is to be used in raising a trailer for instance, by its nondriving rear axle. In order to lock lift post 46 with respect to well 44, a cross pin 58 is provided as shown in FIG. 3 whereby post 46 may be lifted to the selected position and apertures 54 aligned with holes 56, pin 58 then being inserted through the aligned holes and apertures to cause post 46 to be moved from a lowered position to raised positions as the cylinders 14 and 16 are shifted from a lowered position to raised positions. A pair of opposed stops 60 are carried by the outer surfaces 30 and 32 of cylinder walls 34 and 38 for engagement with a lift post stop bar 62 whereby to prevent removal of the lift post 46 from its well 44 and to also prevent unsafe positioning of the lift post. It will be appreciated that pin 58 may be inserted through vertical plates 42 and lift post 46 from either side of the lift inasmuch as it is readily accessible from both sides thereof, this facilitating positioning of the lift post 46 and coupling thereof with the plates 42 and thus with cylinders 14 and 16.

The cylinders 14 and 16 are each identical in internal construction, only one being described hereinafter. Thus, cylinder 14, for example is defined by annular sidewall 34, there being a centrally disposed sleeve 64 disposed within the confines of wall 34, said sleeve serving to support a piston 66 which is essentially the same diameter as the internal diameter of cylinder 14 the piston 66, in turn, supporting a cup-shaped packing seal 68 which fully overlies the normally upper face of the piston 66 to provide a seal between the piston and the inner surface 36 of the cylinder 14.

Sleeve 64, piston 66 and cup seal 68 are fixed with respect to the base 12, this being accomplished by the provision of a stationary center bolt 70 which extends between a threaded boss 72 provided on the normally lower surface of the piston 66 and the base 12, there being a head 74 for drawing said bolt 70 tight whereby to secure the sleeve 64, piston 66 and cup seal 68 with respect to cylinder 14. A plug 71 is welded to piston 66, extends through the piston and beyond the packing seal, and is provided with a retaining ring and washer assembly 76 in overlying relationship to the cup seal 68 whereby to retain the same.

The circumferential edge of piston 66 is provided with a bearing ring 78 which is preferably formed from a suitable plastic material, the ring 78 bearing against the inner surface 36 of the cylinder 14 whereby to prevent metal-to-metal engagement between said surface 36 and the circumferential edge of the piston 66. To further avoid metal-to-metal contact, the cylinder 14 carries an annular cylinder guide 80 on the inner surface 36 thereof, the cylinder guide being provided at its inner most circumferential edge with an annular bearing 82, which is in continuous engagement with the outer face of center sleeve 64.

The packing cup seal 68 is preferably formed from an oil and greaselresistant rubber material and the bearing ring 78 and bearing 82 are formed from a suitable bearing material, the ring 78 and bearing 82 extending sufficiently beyond the surfaces by which they are carried to preclude metal-to-metal contact between any of the components of the cylinder as the cylinder is shifted between its various positions. Furthermore, the provision of the bearing 82 and bearing ring 78 result in the cylinder 14 being able to tolerate a considerable amount of angular misalignment inasmuch as even if such misalignment occurs, the ring 78 and annular bearing 82 will compensate therefor while still preventing metal contact, there being adequate radial clearance between the metal parts of each of the cylinders. Likewise, the cup-type piston seal 68 will accommodate a substantial amount of angular misalignment and still maintain its sealing relationship, thereby permitting continuing functioning of the lift and with little or no relubrication required during normal use thereof.

The lift 10 is provided with a handle 84 which is generally L-shaped in configuration whereby to present a minor leg 86 and a major, longer leg 88, the handle 84 being tubular in cross section whereby air may pass therethrough in a manner for purposes hereinafter described. The handle 84 is provided with gripping members 90 at the free end thereof, said gripping members having a three-way manually controlled spring return air valve 92 disposed therebetween, which valve is covered by a valve cover plate 94 spanning the distance between said gripping members 90, there being an operating lever 96 for said valve 92 carried between said gripping members 90 and in easy reach of the operator of the lift.

The minor leg 86 of handle 84 is pivotally connected to the lift 10 by virtue of a pivot pin 98, which pin connects said leg 86 to a pair of spaced-apart pieces 100 and 102, piece 100 being a rearwardly extending bracket which is secured to the lower surface of the top 48 of the lift, and piece 102 being in the nature of a sector plate which is likewise secured to the lower surface of the top 48, the sector plate being provided with a plurality of radially spaced slots 104, which slots selectively receive a detent 106 which is spring loaded as by torsion coil spring 108 and coupled with a suitable operating rod 110 which is controlled by a lever 112 which forms an extension of the rod 110 and is positioned adjacent the handle-gripping members 90 of the lift 10.

It will be appreciated from the foregoing that, by operation of rod 110, the handle 84 may be swung to any position about its pivot pin 98 and therefore virtually any position with respect to the lift 10, it being contemplated in the embodiment chosen for illustration that four operating positions will be available, these being represented by the four slots 104 in the sector plate 102, the detent 106 serving to lock the handle in any one of the four selected operating positions. When the lift 10 is to be stored, the rod 110 may be actuated whereby to remove detent 106 from any of the slots 104 and handle 84 then may be swung in a generally forward direction about pivot 98 whereby major leg 88 of the handle 84 is in overlying relationship to the top 48 of the lift 10.

The lift 10 is provided with a plumbing system for delivering air from an outside source of compressed air to a point whereby to result in raising of the cylinders 14 and 16. The plumbing system commences with an inlet elbow 114 which is adapted to suitably coupled with a hose by which compressed air can be delivered into the valve 92, the air then passing through said valve 92, when the same is opened through utilization of lever 96, and along the tubular major leg 88 and into tubular minor leg 86. The air then passes from minor leg 86 into a transverse passage 116 formed in rotatable pin 98, and thence along a longitudinal passage 118, through a rotary seal 120 and into a passage 122 drilled in sector plate 102, the air passing from passage 122 through a further passage 124 formed over the wall 38 of cylinder 16 whereby to enter a space 126 which is defined between the cup seal 68 of cylinder 16 and that portion 128 of the top 48 which is in overlying relationship to the piston 66 and seal 68 of cylinder 16.

Once compressed air has reached space 126 it passes outwardly therefrom through a notch in top plate 48 and into passage 132 which is defined by a channel 134 secured to the undersurface of top 48 between the cylinders 14 and 16, and passage 132 delivering the air through a notch formed in the undersurface of top 48 and thence into a space 138 defined between the piston 66 and cup seal 68 of cylinder 14 and that portion 140 of the top 48 which overlies said piston and cylinder.

10 Thus there is provided a plumbing system for delivering air into the lift, which plumbing system is inconspicuous in that it is entirely internal of the lift, utilizing the tubular handle 84, the means for pivotally connecting the handle 84 to the top 48 and the air passage 132 which is formed beneath the top 48 of the lift.

15 It is to be noted that the components of the lift 10 are of such a nature that assembly thereof is facilitated during the manufacturing operation inasmuch as the lift may be inverted from its normal position whereby to commence assembly with

20 the top 48 being lowermost, the cylinders then being positioned thereon in the desired relationship and those components which are received within the cylinder then being positioned by placing them within the cylinders 14 and 16, this being easily accomplished inasmuch as the hole in the base which receives the center bolt 70 is oversize as is the hole in the piston which accommodates the bolt 70, such construction permitting one man to easily assemble the lift 10 and all of the various components thereof and minimizing the effect of misalignment between the base and the assemblies carried thereby.

25 Operation of the lift is achieved by initially positioning the lift post 46 in its desired position whereby to create the necessary overall height for the lift according to the particular purpose for which it is to be used. Actuation of control lever 96 permits air to enter through valve 92 and through the plumbing system hereinabove described into spaces 126 and 138. The air thus admitted shifts the cylinders in an upward direction inasmuch as a force is exerted on those portions 128

30 and 140 of top 48 which are in overlying engagement to the pistons 66 of the corresponding cylinders, such upward shifting serving to move lift post 46 into engagement with the vehicle to be lifted and thence subsequently raise the vehicle. Thus, lift is applied to the vehicle through the centrally located post 46 and, more particularly, pad 50 thereof which is in actual contact with the vehicle to be lifted. When cylinders 14 and 16 are raised as described, the wheels 22 and 28 are lifted out of engagement with the lift supporting surface, such as a floor or the ground, whereby to cause base 12 to be dropped into engagement with such surface and thus support the lift 10 as the cylinders 14 and 16 are moved to their raised positions.

35 The lift is lowered by reverse operation of the control valve 92 by lever 96 which allows the air in the cylinders to exhaust to the plumbing system referred to above. In order to insure full return of the cylinders 14 and 16 to their lowered positions, there are provided a pair of coil return springs 142, said return springs having one end thereof coupled with a lug 144 on the base 12 and the other ends each coupled with a cor-

40 responding lug 146 on the top 48. The return springs are particularly used to return the cylinders and top to a lowered position when the lift post 46 is not loaded and said return springs 142 also serve to prevent separation of the top 48 and the base 12 when the lift 10 is being moved from place to place.

45 Having thus described the invention, what is claimed as new and desired to be secured by Letters Patent is:

50 1. A vehicle lift comprising:
a portable base;
a pair of shiftable cylinders on said base;
means for shifting said cylinders between a lowered position and raised positions;
55 a pair of spaced plates interconnecting said cylinders, said plates cooperating with said cylinders to define a well therebetween;

a lift post received within said well and selectively vertically adjustable therein; and means coupling said post with the plates whereby said post is moved from a lowered position to raised positions as said cylinders are shifted.

2. A vehicle lift as set forth in claim 1, there being a common top for said cylinders, said top having an opening formed therein for said well, said top being shiftable with said cylinders.

3. A vehicle lift comprising:
a portable base;
a pair of shiftable cylinders on said base;
means for shifting said cylinders between a lowered position and raised positions; and
a handle connected to the shiftable portion of said lift, said handle being tubular and having a minor leg and a major, longer leg, said handle being swingable with respect to said cylinders to a position with said major leg overlying said cylinders.

4. A vehicle lift comprising:
a portable base;
a pair of shiftable cylinders on said base;
means for shifting said cylinders between a lowered position and raised positions; and
a handle connected to the shiftable portion of said lift, said means for shifting said cylinder including a compressed air plumbing system, said system including the handle and passage means for delivering air from the handle into the cylinders.

5. A vehicle lift as set forth in claim 4, there being an air inlet valve on one end of the handle and in communication with the handle for delivering compressed air into said plumbing system.

6. A vehicle lift comprising:
a portable base;
a pair of shiftable cylinders on said base, there being a piston within each of said cylinders and a packing seal in normally overlying relationship to each of said pistons,

there being an air-receiving space between each of said seals and the top of the corresponding cylinder;
means for shifting said cylinders between a lowered position and raised positions;
5 a handle connected to the shiftable portion of said lift; and a compressed air plumbing system in communication with said spaces, said plumbing system being defined in part by said shiftable portion of the lift.

7. A vehicle lift as set forth in claim 6, said pistons and said 10 seals being fixed to said base.

8. A vehicle lift as set forth in claim 6, there being a bearing circumscribing each of said pistons and in engagement with the inner faces of corresponding cylinders as the same are shifted with respect to the pistons as a result of introduction of 15 air into said spaces.

9. A vehicle lift as set forth in claim 6, there being at least one return spring interconnecting the fixed base and the shiftable portion whereby to return said cylinders from a raised to a lowered position when air is evacuated from said 20 spaces.

10. A vehicle lift comprising:
a portable base;
a pair of shiftable cylinders on said base;
means for shifting said cylinders between a lowered position 25 and raised positions;
a handle for said lift; and
a pair of wheels carried by each of said cylinder, the pair of wheels proximal to said handle being of larger diameter than the other pair of wheels.

11. A vehicle lift comprising:
a portable base;
a pair of shiftable cylinders on said base;
means for shifting said cylinders between a lowered position 30 and raised positions;
35 a handle for said lift, said handle being pivotally connected to the shiftable portion of the lift and swingable to selected positions with respect to said lift; and
a pair of wheels carried by each of said cylinders.
